ATTORNEY

UNITED STATES PATENT OFFICE.

ARCHIE KEESLING, OF CAMPBELL, CALIFORNIA.

LATCH.

Application filed October 19, 1926; Serial No. 142,658.

This invention relates particularly to door latches.

It is one object of my invention to provide a door fastening mechanism rendered operative or inoperative through manipulation of the door handle.

It is another object of the invention to provide a door fastening means wherein the dead bolt is eliminated and a handle 10 operated latch bolt provided and wherein means is provided for fastening or unfastening the latch bolt by movement of a handle longitudinally of its axis.

It is still another object of my invention 15 to provide a device of the character indicated wherein means is provided for preventing access to and movement of the handle from the side of the door opposite to that upon which it is mounted.

It is also an object of the invention to 20 provide a device of the character indicated that may be readily applied to standard latches without the necessity of altering any of the latch bolt operating mechanism permanently assembled in the latch bolt casing.

Finally it is an object of the invention to 30 provide a simple, economical and highly efficient means for fastening and unfastening a latch bolt through a sliding movement of one of its operating pins, the fastening movement being inwardly toward the said bolt.

In the drawing:

Figure 1 is a sectional view through a portion of a door having a device embodying 35 my invention mounted therein.

Figure 2 is an elevation of one of the door plates embodied in my invention, the spindle member passing therethrough being shown 40 in section.

Figure 3 is an inner elevation of one of the door knobs embodied in my invention, the spindle member mounted therein being shown in section.

Figure 4 is a detail section showing the 45 method of connecting the opposing ends of the latch bar operating pins.

Referring more particularly to the drawing, I show at 1 a portion of a door and at 50 2 a cylinder latch with the latch bar at 3 and the latch bar operating socket at 4. In carrying out my invention I make no alterations in the latch assembly indicated by the reference characters 2 and 3 and the 55 parts inserted therebetween, therefore a detailed description of said parts is not made.

The outer side of the door 1 is indicated by the letter "A" and the inner side by the letter "B".

The outer handle or knob is shown at 5 60 having the bolt operating spindle member 6 mounted therein in the usual manner. In the end of the spindle member 6 is formed a socket 7 extending inwardly a distance along its axis of rotation, and in the said spindle member is mounted a smaller pin 8 passing laterally through the socket 7. Another pin 9 passes through pin 6 at right angles thereto and extends a distance on both sides thereof as shown and spaced back a distance 70 from its end.

A plate 10 is mounted on the door 1 in concentric relation to the spindle member 6 and provided with an orifice 11 through which the spindle member passes. The 75 usual escutcheon is shown at 12.

The inner handle or knob is shown at 13 and fitted with the latch bolt operating spindle member 14 in the usual manner, the said knob having a slot 15 extending diametrically across the face of its shank portion as shown. This spindle member 14 is also fitted with a pin 16 extending a distance from opposite sides thereof and spaced back a distance from its inner end. The 80 said inner end of the spindle member 14 carries an extension 17 adapted to slidably engage the socket 7 in spindle member 6 and provided with a slot 18 through which pin 8 passes. 90

At 19 is shown a plate mounted on door 1 in concentric relation to the spindle member 14 and provided with an orifice 20 through which said spindle member passes. This plate 19 is provided with an outwardly extending annular flange 21 adapted to receive the slotted end of the knob 13 and has lugs 22 formed thereon diametrically opposite to each other and adapted to engage the slot 15 in knob 13. The inner escutcheon is 100 shown at 23.

In assembling the device the two latch-bar operating spindle members 6 and 14 may be joined by inserting pin 17 in socket 7 and then inserting the pin 8 through slot 18. The pin 9 having been inserted in spindle member 6 the assembled parts may be passed through the socket 4 and the pin 16 inserted in spindle member 14. The parts 10 and 12 may now be secured in position and the 105 knob 5 mounted on spindle member 6. The parts 19, 23 and 13 are now placed in posi- 110

tion with the latch-bar 3 extended as shown and the slot 15 in knob 13 engaging the lugs 22 on plate 19. The parts 19 and 23 are now secured in the position placed, the 5 spindle member 14 and knob 13 pulled out to disengage the slot 15 from lugs 22 and the knob secured to the said spindle member 14.

While the parts are in the latter position it is obvious that the latch-bar 3 may be 10 operated in the usual manner, but when the knob 13 and spindle member 14 are pushed inwardly the slot 15 engages the lugs 22 on the fixed plate 19 and these parts are secured against rotation. Since the spindle member 15 14 engages the socket 4 and holds it against rotation with consequent movement of the bar 4 the knob 5 and spindle member 6 are likewise secured against rotation. While the parts are in this position, therefore, 20 neither knob may be rotated and the latch-bar 4 is effectually fastened in an extended position but it may be quickly released by merely pulling the knob 13 out of engagement with the lugs 22.

25 By providing the connection 7, 8, 17, 18 between the latch-bar operating spindle members 6 and 14 the device cannot be unfastened from the outside even though the parts 5, 10 and 12 be removed, because the 30 pin 8 is inaccessible and the slot 18 permits the spindle member 6 to be moved forwardly or backwardly without imparting any movement to the spindle member 14. The pins 9 and 16 engaging the plates 10 and 19 limit 35 the longitudinal movement of the spindle members 6 and 14.

It is to be understood, of course, that while I have herein shown and described but 40 one specific embodiment of the invention, changes in form, construction and method of assembly and operation may be made within the scope of the appended claims.

I claim:

1. A device of the character described, 45 comprising a latch-bar and an operating element operatively connected thereto to advance or retract the same, an operating spindle member engaging said element and movable relative thereto, a fixed support for 50 said device, and interlocking means inserted between the fixed support and movable spindle member and rendered operable by movement of the latter relative to the support.

55 2. A device of the character described, comprising a latch-bar and an operating element operatively connected thereto and a supporting means therefor, a spindle member engaging each end of said operating element and having sliding engagement therewith and with each other, a handle for each spindle member, interlocking means inserted 60 between the supporting means and one of said handles and rendered operative by

movement of the handle relative to the said operating element.

3. A device of the character described, comprising a latch-bar and an operating element operatively connected thereto and a supporting means therefor, a spindle member 70 engaging each end of said operating means and having sliding engagement therewith and with each other, means for preventing disengagement of said spindle members, handles for the spindle members, interlocking means inserted between the supporting means and one of said handles and rendered operative by movement of the handle relative to the operating element.

4. A device of the character described, 80 comprising a latch-bar and an operating element operatively connected thereto and a supporting means therefor, a spindle member 85 engaging each end of said operating means and having sliding engagement therewith and with each other, means for preventing disengagement of said spindle members, handles for the spindle members, a plate mounted on the supporting means and encompassing one spindle member and 90 means inserted in said spindle member for engaging said plate, a plate mounted on the supporting means and encompassing the other spindle member and having an outwardly directed flange formed thereon and 95 lugs formed on the inner surface of said flange, means mounted on said last spindle member for engaging said flanged plate, and means formed on the adjacent handle 100 for engaging said lugs.

5. A device of the character described comprising a latch-bar and an operating element operatively connected thereto to advance or retract the same, an operating spindle member slidably engaging said element, a fixed support for said device, a handle mounted on said spindle member and an escutcheon therefor, a plate mounted on the support beneath said escutcheon, and interlocking means inserted between said 105 plate and said handle.

6. A device of the character described, comprising a latch-bar and an operating element operatively connected thereto to actuate the same, an operating spindle member slidably engaging said element, a fixed support for said device, a handle mounted on said spindle member and an escutcheon therefor, a plate mounted on said support beneath said escutcheon, means mounted on 110 said spindle member on the inner side of said plate adapted to engage the plate and limit the movement of said spindle member and interlocking means inserted between the said plate and handle and rendered operative by an inward movement of the said handle relative to the plate.

ARCHIE KEESLING.
